TOY HOOP ROLLER

James W. Harp, 4950 E. Florence Ave., Southgate, Calif.

Filed Sept. 2, 1964, Ser. No. 81,565

Term of patent 14 years

(Cl. D34—5)

FIG. 1 is a top plan view of a toy hoop roller, showing my new design;

FIG. 2 is a side elevational view thereof; and

FIG. 3 is a bottom plan view of the segmented portion of FIG. 2.

I claim:

The ornamental design for a toy hoop roller, as shown.
